UNITED STATES PATENT OFFICE.

REUBEN JOSEPH ECKSTEIN, OF KITCHENER, ONTARIO, CANADA.

KEY-HOLDER.

1,391,533.

Specification of Letters Patent. Patented Sept. 20, 1921.

Application filed March 31, 1920, Serial No. 370,151. Renewed August 1, 1921. Serial No. 489,356.

To all whom it may concern:

Be it known that I, REUBEN JOSEPH ECKSTEIN, a citizen of the Dominion of Canada, residing at Kitchener, in the county of 5 Waterloo and province of Ontario, Canada, have invented certain new and useful Improvements in Key-Holders, of which the following is a specification.

This invention relates to improvements in 10 key holders for doors and the object is to provide a novel means whereby the key when placed in the door will be held against dropping out or being pushed out from the opposite side of the door.

15 A further object is to provide an inexpensive construction of this nature which can be put on door plates already in use.

With these and other objects in view, the invention consists in the construction, combination and arrangement of parts as will be hereinafter fully described, illustrated in the accompanying drawings, and pointed out in the claims hereunto appended.

Figure 1 is a front plan view of a door 25 plate with my invention shown thereon in normal position,

Fig. 2 is a similar view showing my invention in open position,

Fig. 3 is a detail view of a set of door 30 plates showing the relative position of my invention thereto, the key being shown in dotted position, and

Fig. 4 is a sectional view on the line 4—4 of Fig. 2.

35 Referring to the drawings like numerals designate like parts in the various drawings.

5 indicates a door of any suitable nature on which 6 is a door plate commonly used in connection with the usual locking means. 40 7 is a key hole of any suitable design formed through the plate 6. 8 is a groove formed at one side of the key hole 7 having a deeper depression at its lower end as at 9.

I wish it understood that the hereinbefore 45 mentioned drawings are for illustration purposes only and I have shown my key holder in its simplest form as constructed on the outside of the plate 6 which will be hereinafter described, but I do not wish to 50 limit myself to having my improved key holder constructed on the outside of the plate as it can be operated inside a hollow plate or on a depression formed in the plate 6 which depression would have a covering 55 over the same. In this way it might be bene-

ficial as it would relieve the operating parts from view and from the temptation of tampering with the same.

10 14 is a rod or latch being pivotally mounted as at 11 to the plate 6. Its opposite end 60 is bent inwardly toward the plate 6 as at 12 which end is adapted to reciprocate in the groove 8. This latch when in normal position is as shown in Fig. 1. A suitable spring 14 is used for tensioning the latch to always 65 return to this position when free to do so. I have shown a coil spring 14 but I do not wish to limit myself to the particular design of a coil spring in this particular position as a coil spring might be used in connection 70 with the pivotal connection 11 for tensioning the latch in the same desired manner or a flat spring may be used for the same purpose. 15 is a keeper for holding the reciprocal latch 10 in proper position to the plate 6. 75

The end 12 of the latch 10 is adapted to fit into the depression 9 at the lower end of the groove 8 as shown in Figs. 2 and 4 when it is desirous of leaving the latch in inoperative position.

80 It will be seen that when the key 20 is put through the key hole 7 the operating end 21 cannot be withdrawn when the latch 10 is in the position as shown in Fig. 1 nor can the key be pushed out from the opposite side 85 of the door.

Although I have shown the latch 10 on the outside of the plate 6 in the illustrations, this latch could be as readily attached on the inside of the plate if desired, illustration of 90 which I have omitted as it would be attached in a similar manner as if on the outside as illustrated.

95 From the foregoing it is thought that the construction of my invention will be clearly understood, and, therefore, a more extended explanation has been omitted.

What I claim as new and desire to secure by Letters Patent, is:—

1. In combination with a door plate having a key opening of a latch pivotally connected at one end thereto to traverse the key-opening, a keeper member limiting the motion of said latch, a tension means holding said latch so as to prevent a key from being taken out of a key opening in said plate and a means for holding said latch in inoperative position.

100 2. A pivoted latch member having an angular terminal, a keeper therefor within 110

which it may move, a spring acting to keep the latch in its operative position, and means coöperating with the angular terminal of the latch, said means comprising a plate with a substantially vertical groove having its lower end formed with a deeper depression.

In testimony whereof I affix my signature in the presence of two witnesses.

REUBEN JOSEPH ECKSTEIN.

Witnesses:

A. BOLDUC,
E. A. HERBST.
